UNITED STATES PATENT OFFICE.

ROBERT GIBSON GLASS AND ORRIN HUGH BAKER, OF CHICAGO, ILLINOIS.

TIE PLATE.

Application filed August 26, 1926. Serial No. 131,681.

Our invention relates to a tie plate and has for its primary object the provision of a tie plate which is light in weight, which is easily and cheaply rolled, and which has 5 the metal so distributed that maximum strength is secured with a minimum amount of metal.

Another and further object of our invention is the provision of a tie plate having 10 its greatest thickness of metal in a vertical direction through the tie plate at the points underneath the marginal edges of the rail base where the maximum amount of weight is carried by the tie plate, without abruptly 15 increasing the thickness of the tie plate at these points which, during rolling of the tie plate, is apt to produce a fracture line resulting in the breakage of the plate, thus producing a load sustaining area which is 20 wide enough to withstand the vertical load and also sufficiently strong to meet the resultant lateral thrust of the train wheels.

Another and further object of our invention is the provision of a tie plate having 25 its thickest portions underneath the marginal edge of the rail base with the metal so fashioned or rolled that the tie plate gradually increases in thickness from points of material distance on each side of the bearing point of the tie plate so that a tie plate 30 is formed having great strength and bearing capacity but without a line of crystallization being formed through the metal during the process of rolling thereby rendering the 35 tie plate less liable to break in service.

Another and further object of our invention is the provision of a tie plate somewhat similar to a truss structure so that an arch is formed on the bottom of the tie plate with 40 the tie plate materially reduced in thickness at the central portion thereof, thus doing away with the excess of metal in the middle of the tie plate where less weight is borne by the tie plate and forming in effect 45 a truss in which the load bearing portions of the tie plate are directly underneath the marginal edges of the rails.

Another and further object of our invention is the provision of a tie plate having the 50 usual flat upper rail bearing surface and having on the under side thereof two sub-

stantially wide tie engaging surfaces extending in a direction parallel to the rail base and having a slightly arched structure so that the tie plate is depressed into the fibres 55 of the wood without cutting the fibres or destroying them and yet engaging the tie so that slippage of the plate upon the tie is avoided and any movement relative to the tie plate and tie being overcome, it being necessary in tie plate construction to so fasten the tie plates upon the ties that the tie plates are held integral with the tie as nearly as possible, all movement being between the rail base and the upper side of the tie plate so as 60 to preserve the life of the ties as long as possible.

Another and further object of our invention is the provision of a tie plate which can be rolled in longitudinal strips and 70 thereafter sheared to the proper length without the necessity of cross rolling or machining the plate in order to secure the proper dimensions of the plate so that the cost of manufacture is materially reduced, thereby 75 cheapening the cost of the tie plate to the user.

These and other objects of our invention will be more fully and better understood by reference to the accompanying sheet of 80 drawings and in which:—

Figure 1 is an end elevational view of our improved tie plate; and

Figure 2 is a bottom plan view of our improved tie plate.

The tie plate 10 is shown having the usual rail bearing surface 11 on the upper side thereof and the usual rail abutting shoulder 12, with spike openings 13, 13 therein, through which the usual rail spikes are inserted extending through the tie plate and into engagement with the railway tie.

The under or tie engaging surface of the plate 10 is made up of a plurality of arcuate shaped portions which do not merge into each other, but are separated from each other either by the tie engaging ribs and by a plane surface joining the two arcuate surfaces at the central part of the rail bearing portion of the tie plate. Extending transversely of the plate are a pair of spaced tie engaging ribs 14 and 15, the centers of

these ribs being positioned directly below the marginal edges of the rail base and extending parallel therewith. Beginning at 16 adjacent the inner edge of the rib 14 and extending to 17, is a curved surface 18 conforming to the circumference of a circle having a thirty inch radius, whose center lies in a vertical plane of the center of the rail bearing surface of the plate 10, or which may lie in vertical alignment with the point 17 in the plate, these dimensions being the proper ones for a tie plate of the usual length, viz., 10½ inches, and for other plates of approximately the same length.

Also beginning at 19 on the inner side of and adjacent the rib 15 is an arcuate surface 20 extending towards the other surface 18 and terminating at 21, this surface being similar to the surface 18 and formed on an arc of a circle 30 inches in radius from a center in the vertical plane of the center of the rail bearing portion of the tie plate or in vertical alignment with the point 21 on the under side of the tie plate. Between the points 17 and 21 is a horizontal portion 22 which connects the arcuate surfaces 18 and 20. On the outer side of the rib 14 at 23 an arcuate surface 24 begins and extends approximately to the end of the plate 10, this surface also being formed on a 30 inch radius from a center approximately in vertical alignment with the end of the tie plate 10. On the outer edge of the rib 15 at 25, an arcuate surface 26 begins and extends to the point 27 of the plate from which point to the outer end of the plate a flat surface 28 is formed. The arcuate surface 26 also conforms to the arc of a circle formed with a 30 inch radius having a center in vertical alignment with the point 27 of the under surface of the tie plate. These various arcuate sections of the tie plate form the tie engaging surfaces and are comparatively wide and form a tie engaging surface approximately 2 inches in width on each side of the ribs 14 and 15 in the ordinary 10½ inch tie plate. Throughout the entire length of the tie plate there is no abrupt changing in the thickness of the metal of which the plate is formed and in the formation of the arcuate surfaces the metal is not compressed at any one particular point more than at another or having the metal rolled into a material increase in the thickness of a plate at any particular point so that under constant pounding in service the plate is apt to weaken and crystallize and thereby break at one of these crystallization points.

The flat portion of the plate 22 is formed for the purpose of insuring that the under surface of the plate is in physical contact with the tie throughout the entire under surface thereof, in order that moisture may not collect under the plate resulting in a rotting of the tie. If the plate were arched at the

center thereof, it might also remain out of contact with the tie and allow moisture to collect, and also because it is subjected to constant poundings, as the trains pass over the plate, a fracture of the plate might result.

The arcuate portions of the plate are preferably formed on a thirty inch radius in a tie plate of usual standard length namely 10½ inches. This curvature of the surface is best as it slightly compresses the fibres of the tie without breaking them, and therefore grips the tie without movement between the tie plate and the tie, thereby resulting in less wear and damage to the tie and providing a combination wherein the movement is between the tie plate and the base of the rail.

From the foregoing description it will be understood that the tie plate is formed with its thinnest portion in the middle thereof and at the outer marginal edges of the plate where it is not essential that the plate contain so much metal, and that the thickest portions of the plate, in vertical planes through the centers of the ribs 14 and 15, underneath the marginal edges of the rail base with the surfaces on each side thereof formed in arcs of a circle without an abrupt thickening of the tie plate at any particular place and that the tie plate is thus formed in the form of a truss, thereby adding materially to the strength of the tie plate and affording ample strength of long life to the tie plate in service and further allowing the tie plate to be rolled in a longitudinal direction which can thereafter be sheared to suitable lengths without the necessity of machine work or other milling operations which add to the cost of the tie plate.

While we have described more or less precisely the details of construction, we do not wish to be understood as limiting ourselves thereto, as we contemplate changes in form and the proportion of parts and the substitution of equivalents as circumstances may suggest or render expedient without departing from the spirit or scope of our invention.

We claim:

1. A tie plate having an upper rail bearing surface and a rail abutting shoulder thereon and having a series of arcuate surfaces on the under surface, one pair of said surfaces being separated by a flat bearing surface and other surfaces having tie engaging ribs placed therebetween.

2. A tie plate having an upper rail bearing surface having a rail abutting shoulder thereon and having a lower tie engaging surface composed of a plurality of arcuate shaped portions formed on approximately a 30 inch radius and having tie engaging portions between each of said arcuate surfaces.

3. A tie plate having an upper rail bearing surface having a transversely extending rail abutting shoulder thereon, and having two pairs of arcuate shaped tie engaging surfaces on the under side of said plate, and having a pair of transversely extending ribs formed on said plate, the arcuate surfaces of each pair commencing adjacent said ribs and extending outward therefrom.
- Signed at Chicago, Illinois, this 5th day ¹⁰ of August, 1926.
